UNITED STATES PATENT OFFICE.

MACKINTOSH M. MORRISON, OF CALUMET, MICHIGAN.

MOLDING-MACHINE.

1,195,708.

Specification of Letters Patent. Patented Aug. 22, 1916.

Application filed May 23, 1914. Serial No. 840,545.

To all whom it may concern:

Be it known that I, MACKINTOSH M. MORRISON, a citizen of the United States, residing at Calumet, in the county of Houghton 5 and State of Michigan, have invented certain new and useful Improvements in Molding-Machines, of which the following is a specification, reference being had to the accompanying drawing, forming a part 10 thereof.

This invention relates more particularly to so-called "jolt-ramming machines."

The main objects of the invention are to facilitate the operation of forming sand 15 molds, or packing sand, concrete or the like in molds; to automatically indicate the number of jolts or blows imparted to each mold; to determine and regulate the force of the jolts or blows; to remove the operating 20 mechanism out of reach of sand or other abrasives used in such machines; to provide space below the molding table for drawing the pattern downward from a mold and thus utilizing the table as a stripping plate or 25 support for the sand while the mold is on the table; and generally to improve the construction and operation of machines of this class.

It consists in the construction, arrangement and combination of parts as herein-after particularly described and pointed out in the claims.

In the accompanying drawing like characters designate the same parts in the several figures.

Figure 1 is a side elevation of a machine embodying the invention; Fig. 2 is a plan view and horizontal section on the line 2—2 Fig. 1; Fig. 3 is a vertical section on the line 40 3—3, Figs. 1 and 4; Fig. 4 is a vertical section on the line 4—4, Fig. 3; Fig. 5 is a front elevation of the jolt counter; Fig. 6 is a side elevation of the counter as viewed from the left relative to Fig. 5, the pivoted ratchet 45 cover and pawl carrier being shown in vertical section on the line 6—6, Fig. 5; Fig. 7 is a vertical section on the line 7—7, Fig. 5; Fig. 8 is a horizontal section on the line 8—8, Fig. 6. Fig. 9 is a 50 detached side view of the table lifting lever with which the operating connection is made; Fig. 10 is a partial side elevation similar to Fig. 1, showing a different arrangement of the counter and table lifting rod; Fig. 11 is a view similar to Fig. 3, showing 55 a modification of the pattern carrier for a

pattern having no adverse draft; and Fig. 12 is a partial side elevation similar to Fig. 1 showing a modification of the molding table. 60

Referring particularly to Figs. 1, 2, 3 and 4, the machine comprises a base 1, and a vertically movable molding or mold jolting table 2, removably mounted and guided thereon. The downward movement of the 65 table is limited by impact stops 3, consisting of four hardened steel anvils secured in sockets 4 on the base and fitting at their upper ends freely in sockets 5 on the under side of the table, thus affording guides for 70 the table in its vertical movement. In the sockets 5 are inserted and fixed hardened steel impact pieces 6, which normally rest on the anvils or stops 3, as shown in Fig. 1. The table 2, is connected with the base 1, by 75 lifting and dropping mechanism consisting of four bell crank levers 7 and 8, having vertically and horizontally disposed arms of the same length. The levers 7 are mounted and fixed on a rocker shaft 9, and their vertically 80 disposed arms are connected by horizontal links 10 with the corresponding arms of the levers 8. The shaft 9 is journaled and supported in bearings 11 on the base below and parallel with one side of the table and is 85 provided with an arm 12, which may be formed with one of the bell crank levers 7, as shown in Figs. 1 and 9. The levers 8 are fulcrumed at their elbows on pins 13, held in alinement with each other and parallel with 90 the shaft 9, in forked posts 14 on the base 1. The horizontally disposed arms of the levers 7 and 8 are connected by vertical links 15 with the table 2, the table being detachably connected with the upper ends of these links 95 by pins 16.

A horizontally disposed operating lever 17, fulcrumed in a forked post 18, on the base 1, is connected at the end of its shorter arm by a link 19 with the arm 12 on the 100 rocker shaft 9. The longer arm of the lever 17 normally rests, as shown in Fig. 1, on a rubber or elastic bumper 20, mounted on the base 1, and it is formed on the under side with a series of notches or seats 21, 21', 21'' and 21''', at different distances from its fulcrum.

An actuating cam 24, mounted on an overhead driving shaft 25 above the lever 17, is preferably formed as shown in Fig. 1, with 110 a number of arms or projections, in which are mounted equidistant from one another,

rollers 26. An arm or wiper 27, pivoted at 28 to a suitable support and limited in its downward movement by a stop 29, is adapted to coöperate with the rollers 26 of the 30 cam 24, for lifting and dropping the table 2, as hereinafter explained. A pendant lifting rod 30, is pivoted at its upper end to the wiper arm 27, and is provided at its lower end in a forked head 31, with a roller 32, which is movable into and out of operative engagement with the lever 17 and into any of the notches or seats 21—21''' in the under side thereof, at different distances from the fulcrum of the lever so as to vary 35 the lift of the table 2 and the force of its impact on the anvils or stops 3. The lifting rod 30 is shifted into and out of engagement with the lever 17 and into different engaging positions therewith, by a hand lever 33, 40 mounted on the base 1 adjacent to the table 2, and connected by a rod 34 with the rod 30. To lock and hold the rod 30 in its different positions, the hand lever 33 is provided with a spring actuated detent 35, 45 adapted to work with a notched arc 36, and connected with a grip lever 37 fulcrumed on the lever 33 adjacent to its handle. To lift and hold the wiper 27 out of the path of the cam rollers 26, when the jolting mechanism is not in use, the base 1 is formed or 50 provided as shown in Fig. 1, with an inclined guide and rest 38, upon which the roller 32 rides when the lifting rod 30 is swung and locked by the lever 33 out of operative engagement with the lever 17.

The forked head 31 has a threaded connection with the lower end of the rod 30, as shown in Fig. 1, so that it may be adjusted to prevent lost motion between the lifting 40 rod and the lever 17 when the roller 32 is shifted into engagement with the notch or seat 21''' to produce the maximum lift of the table 2.

The arrangement of the guiding and lifting connections between the table and base as hereinbefore described, provides ample space for drawing the pattern downward from the mold through an opening in the table or the stripping plate with which the 50 table is provided and on which the mold rests, an expedient which in certain cases facilitates the operations of molding. It also avoids the difficulties and objections incident to the employment of a fluid pressure or other motor underneath the table, where it is subjected to excessive wear on account of exposure to sand or other abrasives falling from the table. The actuating mechanism, consisting of the rotary cam 55 24 and wiper 27, are in this case located overhead out of reach of sand or other abrasives used in molding. Any number of machines may be operated independently of one another by cams on the same driving 60 shaft 25, the operation of each machine be-

ing controlled by shifting the rod 30 into and out of engagement with the lever 17 of that machine.

In molding of the kind in which it is advantageous or desirable to draw the patterns 70 downward from the molds while they rest on the molding table 2, the machine is provided with a table which is formed with an opening corresponding in size and shape with the pattern, and which serves as a 75 stripping plate, or as shown in Figs. 2, 3 and 4, it may be formed with an opening somewhat larger than the pattern and provided with a separate stripping plate or plates 38, countersunk in the top of a table 80 flush with its upper surface and formed with an opening corresponding in size and shape with the pattern. The table is also provided with a vertically movable pattern carrier 39, guided on ways 40, fastened to 85 and depending from the under side of the table and connected at their lower ends by a yoke or cross piece 41. The pattern carrier is connected by links 42 with a crank shaft 43, journaled in a bearing on the yoke 90 or cross piece 41. When the pattern *p* has no adverse draft it may be bolted or otherwise immovably fastened to the carrier 39 as shown in Fig. 11, but when it is of such shape that it has adverse draft, or cannot 95 be directly drawn from the mold, it is made in sections and movably mounted on the carrier as shown in Figs. 3 and 4.

For the purpose of illustration a pattern 100 for molding the upper part of a stamp shoe with a dove-tailed projection, is shown. This pattern is made in two sections 44, which are parted transversely through the dove-tailed projection and are movable horizontally toward and from each other. They 105 are formed as shown in Fig. 4, with tongues 45, which are fitted and guided in horizontal grooves in opposite sides of the carrier 39. The two sections are connected by nuts 46 with right and left screws mounted on a 110 shaft 47, which is journaled in bearings in the carrier 39 parallel with the crank shaft 43, and on which the upper ends of the links 42 are pivoted. The outward or opening movement of the sections 44 is limited by the engagement of lugs 48 with the table or stripping plate 38, as shown in Fig. 3, and their inward or closing movement is limited by the engagement of the inner ends of the sections with each other. As shown in Fig. 115 3, the shafts 43 and 47 are squared at one end to receive a socket wrench.

A flask 49, of suitable form and construction for the pattern and mold, is placed on the table 2, its position being determined by 125 notches in the bottom of the flask fitting over corresponding tapered studs or lugs 50, projecting from the top of the table, as shown in Figs. 1 and 3.

To indicate the number of jolts to which 130

each mold is subjected the machine is provided with an automatic counter or indicator comprising a graduated scale, an index movable over the scale, ratchet mechanism for operating the index and means for returning the index to its initial position when the jolt-ramming mechanism is stopped.

Referring to Figs. 1 and 5 to 8 inclusive, the jolt counter is preferably constructed as follows: The index or pointer 51 is attached to one end of a shaft or spindle 52, journaled as shown in Fig. 7, in bearings on a frame 53. The frame 53 is secured at one end, as indicated in Fig. 5, to a post or other convenient support. The shaft 52 is provided between its bearings with a drum 54, and at the end opposite the index with a crown ratchet wheel 55. Front and back plates 56 and 57 are fastened to the frame 53 parallel with each other, and on the front plate 56 is formed or mounted a graduated dial or scale 58. A weight 59, is suspended by a flexible band 60 from the drum 54 in such a way that when the index is released it will be returned to its initial position at zero on the dial, as shown in Fig. 5. The weight 59 is guided and inclosed with the band 60 in a vertical casing or guideway 61, attached at its upper end to the frame 53. A ratchet cover or plate 62, is hinged or pivoted at its upper end to the back plate 57, over the ratchet wheel 55, and is provided with a vertically movable slide or pawl carrier 63, which is connected, as shown in Fig. 1, by a rod 64, with the wiper arm 27. The slide 63 is provided with a pivoted operating pawl 65, adapted when the slide is reciprocated by the vibratory movement of the wiper arm, to engage with and turn the ratchet wheel 55 step by step, and advance the index 51 an interval on the dial 58 for every up and down movement of the wiper. The pawl 65 is yieldingly held by a spring 66 in operative position relative to the slide 63. A holding pawl 67, pivoted to the ratchet cover or plate 62, as shown in Fig. 8, is yieldingly held by a spring 68 in engagement with the ratchet wheel 55 to prevent backward movement thereof when the operating pawl 65 is active and the ratchet cover or plate is in operative position, as shown in Figs. 6 and 7. The ratchet cover or plate 62 is connected at its lower end with a sliding rod 69, which is guided in the front and back plates 56 and 57, as shown in Figs. 6 and 7. A spring 70, surrounding this rod and bearing at its ends against the back plate 57 and a collar on the rod, tends to hold the ratchet cover or plate in operative position against the back plate.

The counter is so arranged that the pendant lifting rod 30 when shifted into inoperative position, as shown in Fig. 1, will move the ratchet cover or plate 62 away from the

back plate 57, and will carry and hold both pawls 65 and 67 out of engagement with the ratchet wheel 55, thereby allowing the weight 59 to return the index 51 to its initial or zero position. The counter may be placed behind the rod 30 as shown in Fig. 10, so that the front end of the rod 69 will be engaged thereby, and the ratchet cover or plate 62 will be shifted with the pawls into inoperative position when the rod 30 is shifted into inoperative position, or the counter may be located in front of the rod 30 and the rod 69 connected therewith by a flexible strap 71 or the like, so that when the rod 30 is shifted into inoperative position the ratchet cover or plate 62 with the pawls, will also be shifted into inoperative position, as shown in Fig. 1.

To prevent the overwinding of the band 60 on the drum 54 and injury to the counter mechanism, a trip 72 is pivoted in an opening in the back plate 57, and is located with its lower free end opposite the rim or lower edge of the ratchet cover or plate 62, as shown in Fig. 7. The back of the trip, which projects into the guideway 61, is inclined, so that when the weight 59 is lifted into engagement with the trip it will thrust the ratchet cover or plate away from the back plate 57, and shift the holding pawl 67 out of engagement with the ratchet wheel 55, thereby arresting the advance movement of the ratchet wheel by the operating pawl 65, even if the table lifting and jolting mechanism continues in operation.

In the operation of the machine equipped with a separable sectional pattern for adverse draft such as is used for molding stamp shoes and the like, and with pattern drawing mechanism as hereinbefore described, the pattern being elevated with the pattern carrier 39 into operative position as shown in Figs. 3 and 4, and the pattern being closed, a flask 49 is placed in position on the table and filled with molding sand. The operator throws the hand lever 33 to the right as shown in Fig. 1, thereby shifting the pendant lifting rod 30 into operative engagement with one of the notches 21, 21', 21'', 21''', in the under side of the lever 17, which may for example, be made to lift and drop the table 2 three-eighths, one-half, five-eighths and three-fourths of an inch, the lift and drop increasing as the roller 32 is shifted toward the fulcrum of the lever 17. As the roller 32 clears the rest 38 and engages the lever 17, the wiper 27 being lowered into the path of the rollers 26 of the cam 24 is lifted and dropped in rapid succession according to the speed of the cam, say 250 times per minute. The operating lever 17 being vibrated in unison with the wiper 27 acting through the bell crank levers 7 and 8 and their connections, lifts and drops the table 2 upon the

anvils or impact stops 3, thereby jolting the table and ramming and packing the sand in the flask above and around the pattern. The extent of the lift and drop of the table, which determines the force of the jolts or blows of the impact pieces 6 on the anvils or stops 3 and the number of jolts to which a mold of any given kind is subjected, are varied according to the character of the work. A low drop repeated enough times is effective to pack the sand in the flask with approximate uniform density from top to bottom, while a high drop, which is more expeditious, packs the sand harder around the pattern, a condition which should be avoided, especially in some kinds of work. With each up and down movement of the wiper 27, the operating pawl 65 of the counter actuated by the rod 64, turns the ratchet wheel 55 and the index 51 forward or clockwise, the distance of a division on the dial or scale 58, the ratchet wheel having as many teeth as there are divisions on the dial or circular scale. When the operation of jolt ramming a mold has been continued long enough, as for example, when the counter indicates 125 jolts, which occurs in thirty seconds after the machine is started, if the cam 24 makes 250 revolutions per minute as assumed, the operator throws the lever back to its initial position at the left, as shown in Fig. 1, the detent or latch 35 dropping into the single notch at the left in the arc 36 and locking the lifting rod 30 and the wiper 27 in inoperative position with the roller 32 on the rest 38. The operation of the table lifting and dropping mechanism is thus arrested, the table resting in its lower position with the impact pieces 6 on the anvils or stops 3. As the rod 30 is turned back to its initial position by the operator, it swings the ratchet cover or plate 62 away from the back plate 57 of the counter, carrying both pawls 65 and 67 out of engagement with the ratchet wheel 55 and releasing the index 51, which is returned to its initial zero position, as shown in Fig. 5 by the weight 59. The pattern is then spread or opened by separating the sections 44 to enlarge the imprint of the dovetailed projection in the sand, so that when the pattern is closed or the sections 44 brought together, the pattern may be drawn downward from the mold on the table 2. To accomplish this, a socket wrench is applied to the squared end of the shaft 47 through openings made therefor in the flanges of the table, as shown in Fig. 3, and the shaft is first turned in a direction to separate the sections 44, the opening movement being limited by the engagement of the lugs 48 with the table 2 or stripping plate or plates 38. The shaft 47 is then turned in the reverse direction till the sections 44 are brought together. The crank shaft 43 is then turned a half revolution

with the wrench, and the pattern is thus drawn downward from the mold through the opening in the table. The flask is now removed from the table and assembled with a cast iron chiller for pouring or filling the mold and casting a stamp shoe with the lower portion thereof hardened. After the mold has been removed, the pattern, which is left closed, is elevated with the carrier 39 into operative position above the table by turning the crank shaft 43 back to its original position, as shown in Figs. 3 and 4. Another flask is placed in position on the table, filled with sand and jolt-rammed as above explained.

In molding with a pattern which has no adverse draft and which is immovably attached to the carrier 39, after the jolt-ramming operation has been completed, the pattern is drawn downward directly from the mold by turning the crank shaft 43, as above explained. For this kind of molding the nuts 46 and the right and left screws with which they work, may be omitted as shown in Fig. 11. With a plain table 2' having no opening therein, which as shown in Fig. 12 may be readily substituted for a table like that shown in Figs. 2, 3, 4 and 11, the flask with pattern, after it has been jolt-rammed with sand, is removed from the table and turned upside down to remove the pattern.

Various changes in the details of construction and arrangement of parts of the machine other than those specifically shown and described may be made without departure from the principle and scope of the invention as defined in the following claims.

I claim:

1. In a molding machine the combination of a base, a vertically movable molding table mounted and guided thereon, interconnected lifting levers connecting said table and base, and an overhead drive shaft having an actuating adjustable connection for vibrating said levers and successively lifting and dropping said table.

2. In a molding machine the combination of a base, a vertically movable molding table mounted thereon, bell-crank levers connecting said base and table, an operating lever connected with said bell-crank levers, an overhead shaft provided with a cam, and a wiper arranged to coöperate with the cam and having a connection with the operating lever adapted to successively lift the table.

3. In a molding machine the combination of a vertically movable molding table, interconnected lifting levers connected with said table, impact stops arranged to limit the downward movement of the table, and an overhead driving cam having a detachable connection with said levers and adapted to successively lift the table and permit it to drop on said stops.

4. In a molding machine the combination

of a vertically movable molding table, interconnected lifting levers connected with said table, impact stops for limiting the downward movement of the table and jolting the same, a driving connection adapted to actuate said levers for lifting and dropping the table successively, and means for varying the movement of said levers by said driving connection to vary the force of the jolts.

5. In a molding machine the combination of a vertically movable molding table, lifting mechanism connected with said table, impact stops for limiting the downward movement of the table and imparting jolts thereto, an operating lever connected with the lifting mechanism, an overhead drive shaft provided with a cam, a wiper arranged to coöperate with the cam, and a pendant rod connected with the wiper and movable into and out of operative engagement with said operating lever.

6. In a molding machine the combination of a vertically movable molding table, impact stops for limiting the downward movement of the table with jolts, lifting mechanism connected with said table and comprising a lever, an actuating cam, a wiper arranged to coöperate with said cam, and a rod connected with said wiper and movable to engage said lever at different distances from its fulcrum for varying the lift of the table.

7. In a molding machine the combination of a vertically movable molding table, impact stops for abruptly limiting the downward movement of the table, lifting mechanism connected with the table and comprising a lever, an actuating cam, a wiper arranged to coöperate with the cam, a rod connected with said wiper and movable into and out of operative engagement with said lever and into engaging positions at different distances from its fulcrum, and means for shifting said rod and holding it in its different positions.

8. In a molding machine the combination of a vertically movable molding table, impact stops for limiting the downward movement of the table with a jolt, lifting mechanism connected with the table and comprising a lever, an actuating cam above said lever, a vertically movable wiper adapted to coöperate with the cam, a rod pivotally connected at its upper end with the wiper and movable at its lower end into and out of operative engagement with said lever, and a rest adapted by engagement with said rod when it is shifted out of engagement with the lever, to lift and hold the wiper out of operative relation to the cam.

9. In a molding machine the combination of a vertically movable table, impact stops for limiting the downward movement of the table, lifting mechanism connected with the table and comprising an operating lever, an

actuating cam, a wiper adapted to coöperate with the cam for lifting the table, a rod pivotally connected with the wiper and movable into and out of operative engagement with said lever and into different engaging positions, a hand lever connected with said rod for shifting it into different positions, means for locking the hand lever in different positions, and an inclined guide rest adapted by engagement with said rod when it is shifted to inoperative position to lift and hold the wiper out of the path of the cam.

10. In a molding machine the combination of a base, a vertically movable table, impact stops for limiting the downward movement of the table fixed to one of the parts and freely fitting guide ways in the other, bell crank levers fulcrumed at their elbows on the base, links connecting the horizontally disposed arms of said levers with the table, links connecting the vertically disposed arms of said levers in pairs, and means for rocking said levers to lift and drop the table.

11. In a molding machine the combination of a base, a vertically movable table, impact stops for limiting the downward movement of the table, bell crank levers mounted on the base and having vertically and horizontally disposed arms, two of said levers being fixed on and connected by a rocker shaft which is provided with an arm, links connecting the vertically disposed arms of the levers on the rocker shaft with the corresponding arms of the other levers, links connecting the table with the horizontally disposed arms of said levers, a horizontally disposed and vertically movable operating lever connected with the arm on the rocker shaft, a cam, a wiper arranged to coöperate with the cam for lifting and dropping the table, a rod pivotally connected with the wiper and movable to engage with the operating lever at different distances from its fulcrum, and means for shifting said rod into its different positions.

12. In a molding machine the combination with jolting mechanism and means for starting and stopping said mechanism at will, of a jolt indicator comprising a movable part having an actuating connection with a reciprocating part of the jolting mechanism, means tending to return said movable part of the indicator to its initial position, and means operated by said starting and stopping means adapted to release said movable part of the indicator and permit it to return to its starting position whenever the jolting mechanism is stopped.

13. In a molding machine the combination of a vertically movable mold jolting table having an opening therein and provided with a vertically movable pattern carrier guided therein, lifting mechanism connected with the table, means for raising and

lowering said carrier relatively to the table, pattern sections guided on said carrier and movable toward and from each other, and means for opening and closing the pattern while it is in a mold.

14. In a molding machine the combination of a vertically movable table, having an opening therein and provided with a vertically movable pattern carrier guided in the table, a crank shaft journaled in a bearing suspended from the table and connected by links with the pattern carrier, and lifting mechanism connected with the table.

15. In a molding machine the combination of a vertically movable table having an opening therein, lifting mechanism connect-

ed with the table, a vertically movable pattern carrier guided on ways extending downwardly from the table, pattern sections guided on the pattern carrier and movable horizontally toward and from each other, a shaft journaled in the pattern carrier and provided with right and left screw threads, and nuts engaging said threads and connected with the pattern sections for opening and closing the pattern.

In witness whereof I hereto affix my signature in presence of two witnesses.

MACKINTOSH M. MORRISON.
